UNITED STATES PATENT OFFICE

123,599

DESIGN FOR A CAN PERFORATOR

John A. Kick, Chicago, Ill.

Application March 27, 1940, Serial No. 91,280

Term of patent 7 years

To all whom it may concern:

Be it known that I, John A. Kick, a citizen of the United States, residing at Chicago, in the county of Cook and State of Illinois, have invented a new, original, and ornamental Design for Can Perforator, of which the following is a specification, reference being had to the accompanying drawing, forming a part thereof.

Fig. 1 is a side elevation of the can perforator, showing my new design; and

Fig. 2 is an end elevation of the same.

I claim:

The ornamental design for a can perforator, as shown.

JOHN A. KICK.
